UNITED STATES PATENT OFFICE.

JAMES E. McDADE, OF CHICAGO, ILLINOIS.

EDUCATIONAL CHART.

1,323,779.

Specification of Letters Patent.

Patented Dec. 2, 1919.

Application filed June 12, 1919. Serial No. 303,647.

To all whom it may concern:

Be it known that I, JAMES E. McDADE, a citizen of the United States, residing at Chicago, in the county of Cook and State of Illinois, have invented certain new and useful Improvements in Educational Charts, of which the following is a specification.

My invention relates to an improvement in educational charts of the type which may be hung on the wall of a room and which are provided with a plurality of horizontal and parallel grooves adapted to receive and hold removable display cards having letters, words, numerals or other characters printed thereon by means of which words, sentences, problems, and other exercises may be formed and exhibited to the pupils. My invention relates particularly to the construction of the grooves for holding the cards on the chart.

Various attempts have been made to provide means to hold the display cards on a chart of the type mentioned including, for example, the method of bending back and overlapping paper to form grooves, providing pockets by notching and interlocking strips of paper, forming a groove in a strip of non-resilient material and securing the strip to a frame, providing wire clips of various kinds on the chart or by pasting a strip of card board along its lower edge to the body of the chart leaving the upper edge free to form a groove. Such attempts, however, have not been successful because, in practice, the card holding means, when made of paper, soon lose their gripping action, when made of non-resilient material the parts soon become worn to such an extent that the display cards are not firmly held in place and when made of wire clips the construction is not only expensive but the clips tend to work loose in the body of the chart so that with any of the devices of the prior art the display cards after a relatively short period of use are not held firmly in an upright position but incline or tilt forwardly which, obviously, is objectionable in a device of this kind.

The principal object of my invention is to provide a chart preferably having a plurality of horizontal and parallel grooves of simple and inexpensive construction for holding the display cards, the grooves being constructed so that the front wall of each groove serves to prop or hold the display cards up against the body of the chart

thereby preventing them from tilting forwardly.

A further object of my invention is to provide grooves having a flat smooth bottom so that the display cards may be easily alined on the chart.

My invention will be better understood by reference to the accompanying drawing illustrating a certain preferred embodiment, wherein—

Figure 1 is a perspective view of a fragmentary portion of a chart embodying the principles of my invention, and

Figs. 2 and 3 respectively are cross sectional views taken on lines 2—2 and 3—3 of Fig. 1.

Like characters of reference designate like parts in the several views.

The chart preferably consists of a plurality of rectangular strips 5, 5^a, 5^b, etc., joined together so as to provide a plurality of horizontal parallel grooves 6, 6^a, 6^b, etc., in which a number of removable display cards 7, 7 bearing printed letters, words and numerals may be placed. The parts are preferably made of card board of suitable thickness although any other suitable material might be used. The grooves are identical in construction and it will suffice to describe in detail the construction of the groove 6 formed by the overlapping edges of the strips 5 and 5^a. Each groove is preferably formed by securing the front side of the upper strip 5 along its lower edge *x* to the back of a relatively narrow strip 8 and the front side of the strip 8 is secured to the back of the adjacent lower strip 5^a a short distance below the upper edge *y* thereof so that the upper free edge of the strip 5^a forms the front wall and the upper strip 5 forms the back wall of the groove 6. The strips of card board are preferably secured together by means of paste or glue. The thickness of the upper edge of the strip 8, preferably, is considerably less than that of the lower edge thereof, the sides of the strip 8 running down on a straight taper. The upper edge *y* of the strip 5^a is inclined backwardly toward and nearly touches the front side of the upper strip 5 the natural inclination of the upper portion of the strip 5^a being to lie in a plane parallel with the front side of the tapered strip 8 (Fig. 2). The chart may be reinforced by pasting a strip 10 of paper or cloth 10 over the back of the strips 5 and 5^a.

110

Preferably the display cards 7, 7 are substantially equal in thickness to that of the upper edge of the strip 8. When the display cards 7, 7 are placed in the groove 6, 5 the upper edge of the strip forming the front wall of the groove is sprung outwardly out of its natural inclined position (Fig. 3) with the resultant tendency of the upper edge of this strip to crowd and hold the 10 display cards 7, 7 in an upright position against the front side of the adjacent upper strip. The upper edge of the strip 8 forms a flat smooth bottom for the groove 6 so that the display cards may be easily placed in 15 alinement.

The chart may be suspended by a wire or cord 11 from a hook on the wall of a room. I have found that a chart embodying the 20 principles of my invention will stand considerable use without the upper edges of the strips forming the front walls of the grooves losing their resiliency. When the chart is 25 constructed of card board the display cards are firmly propped or held up against the body of the chart in an upright position and in alinement.

I claim:

1. In an educational chart, the combination of upper and lower horizontal strips, 30 the bottom edge of the upper strip overlapping the upper edge of the lower strip, and a relatively narrow strip secured therebetween, the upper edge of said lower strip extending upwardly beyond said narrow 35 strip to provide one wall of the groove formed between said upper and lower strips, the upper edge of said narrow strip providing a flat smooth bottom for said groove, said groove being adapted to receive display 40 cards bearing printed matter

2. In an educational chart, the combination of upper and lower horizontal strips, the bottom edge of the upper strip overlap-

ping the upper edge of the lower strip, and a relatively narrow strip secured therebetween, the upper edge of said lower strip extending upwardly beyond said narrow strip and inclined toward said upper strip to provide one wall of the groove formed between said upper and lower strips, said 45 groove being adapted to receive display cards bearing printed matter, the upper edge of said lower strip holding said display cards up against said upper strip.

3. In an educational chart, the combination of upper and lower horizontal strips, the bottom edge of each of said strips being overlapped by the upper edge of the adjacent strip therebelow, and relatively narrow horizontal strips secured between 60 the respective overlapped edges, the upper edge of each of said lower strips extending upwardly beyond the respective narrow strips and inclined toward the adjacent upper strip thereabove to provide one wall of 65 the groove formed between said adjacent upper and lower strips, said grooves each being adapted to receive cards bearing printed matter.

4. In an educational chart, the combination of a plurality of upper and lower horizontal strips, the bottom of each of said strips being overlapped by the upper edge of the adjacent strip therebelow, and relatively narrow strips secured between the respective overlapped edges, the upper edge of 75 said lower strips extending upwardly beyond the respective narrow strips to provide one wall of the groove thereby formed between the adjacent upper and lower strips, 80 the upper edge of each of said narrow strips providing a flat smooth bottom for the groove, said grooves being adapted to receive display cards.

JAMES E. McDADE.
